UNITED STATES PATENT OFFICE.

CHARLES H. CAMP, OF BROOKLYN, NEW YORK, ASSIGNOR TO THE DELAWARE, LACKAWANNA & WESTERN COAL CO., OF NEW YORK, N. Y., A CORPORATION OF NEW JERSEY.

METHOD OF AND APPARATUS FOR HEATING CLAY PRODUCTS IN KILNS OR OVENS.

Application filed June 30, 1927. Serial No. 202,609.

This invention relates to a method of and apparatus for heating clay products in kilns or ovens, and particularly to the controlled distribution of the combustion gases employed so that the products can be subjected to regulated and uniform heating. The invention is adapted to the operation of brick kilns and will be described more especially with relation thereto although it may be utilized with advantage in kilns and ovens in which other clay and similar products are heated or fired.

The burning of bricks is conducted, according to a long established practice, in kilns either of the "scove" or "bee-hive" types. In the former type, which is commonly used, the bricks are assembled in a honey-combed pile which is arranged to leave arched openings or tunnels in the bottom of the pile. Grates are provided in these openings and fires are established therein. Since the kilns are from thirty to forty feet in length, it is obviously impossible to maintain satisfactory control over a fire or fires extending throughout the length of the tunnels and to intensify or reduce the amount of heat produced at different zones of the fire or fires in accordance with the varying requirements of the kiln. Furthermore, it is impracticable to burn the cheaper grades of fuel which clinker and require cleaning on grates exceeding a length which is determined by the ability of operators to keep the fires in good condition. It is usual, therefore, to burn the larger sizes of coal on grates at opposite ends of the tunnels with a "dead space" between and to depend upon the regulation of draft and the opening of fire doors at one or both ends of the tunnels, with heavier or lighter firing at different points, to effect the desired distribution of the heat. Such operation results in a waste of fuel due to the introduction of a large excess of cold air which must be heated by the fires. Moreover, the method depends principally on radiation and conduction to carry the heat to parts of the kiln which are not in the normal direct line of travel of the hot gases from the grates. Consequently the arches above the fires must be over-heated to a considerable degree. The uneven burning results in wide variation of the color and quality of the bricks, ranging from blackened hard-heads to soft partly-burned brick. It may even cause the arches

to fall and thus necessitate drawing the fires until the arches can be repaired. The practice as described sacrifices efficient firing and accomplishes only a very crude, uneconomical and uncertain control over the distribution of heat in the kiln.

In the "bee-hive" type of kiln the grates are usually disposed in furnaces adjacent to the permanent walls of the kilns and the gases are introduced to tunnels or flues in the kiln. The same difficulty of securing uniform distribution of the heating gases is experienced, and the product is not uniform.

Kilns and ovens employed for heating other clay and similar products, whether such products are arranged in piles or upon supporting racks, are equally defective in respect to the distribution of the heating gases. The gases tend to follow the shortest path through the kiln in direct contact with only a portion of the contents. The heating of the remainder of the product depends primarily upon radiation and conduction.

Another defect of kilns and ovens as operated heretofore is the impracticability of burning the smaller sizes of hard coal such as pea and buckwheat and the cheaper grades of bituminous coal therein. Such coal can be burned for kiln or oven heating only with forced draft and this accentuates the difficulty of distributing the combustion gases to secure uniform heating of the product. The forced draft carries the hot gases through the shortest and most direct path to the stack in a "bee-hive" type kiln or to the open air in a "scove" type kiln with the result that parts of the kiln in such path are overheated and other parts remain at comparatively low temperatures. To heat parts of the kiln which are not in the direct path of the gases the temperature in other parts must be so high that some of the product is destroyed. Consequently it has been customary to burn only wood or expensive grades of soft coal of the expensive sizes of anthracite or to resort to the more expensive gas or oil fuels.

It is the object of the present invention to provide improvements in kilns and the like and in the operation thereof whereby the hot combustion gases can be distributed more uniformly and the heating effect thereof can be regulated to permit satisfactory heating of all of the product in the kiln.

Another object of the invention is to per-

mit the burning of hard coal in small sizes or the cheaper grades of bituminous coal so that the cost of operation can be reduced.

The advantages of the invention are a more uniform product, a considerable saving resulting from prevention of overheating and underheating of the product, and saving in labor, in repairs to the kiln, and particularly in the time required to complete the heating of the product. These and other advantages which have been demonstrated in actual operations permit a substantial reduction in the cost of clay and similar products which require burning and like heat treatment.

In carrying out the invention the hot combustion gases are drawn from the grates or furnaces toward the "dead space" of the kiln, that is to say, from a part thereof which is not in the normal direct line of travel of the gases through the kiln, by withdrawing a portion of these gases from the "dead space" under the influence of suction applied at that place. The withdrawal of some of the gases induces a flow of the hot gases away from the grates or furnaces and consequently the heat there generated or any portion thereof can be conveyed toward a section of the kiln to which the gases would not otherwise thoroughly penetrate. By variation of the suction and consequent flow of gases the heat can be directed at will throughout the length of the tunnels, for example, and uniformity or a variation of heating as required can be assured.

To avoid loss of the heat carried by the gases which are withdrawn from the "dead space", such gases are recirculated and discharged again into the tunnels or furnaces and there mingled with fresh combustion gases. Thus, a constant circulation of hot gases from the grates or furnaces toward the normally cooler zones of the kiln can be maintained and the escape of gases at relatively high temperatures can be avoided.

The recirculated gases can be introduced either wholly or in part above or below the grates, but preferably such gases are introduced above the grates. Air can be introduced and mingled with the hot combustion gases before they are returned to the furnaces or tunnels either to aid secondary combustion of any combustible gases which may be present or to maintain desired oxidizing conditions in the kiln, or ingress of air can be eliminated, in which case a reducing atmosphere (deficiency of oxygen in the products of combustion) can be maintained. Thus, in brick kilns for most kinds of brick it is necessary to introduce air with its constituent oxygen at certain stages of the operation in order that the proper oxidizing conditions may be present for development of desired color in the brick, or where coal dust is mixed with the clay mixture, oxygen

is necessary for the burning of same. The air can be introduced either with the recirculated gases or separately.

Normally in operating with hard coal, in the finer sizes and similar fuels, a forced draft must be employed. Air for this purpose can be introduced below the grates under suitable pressure. The recirculation of the gases as described assists in maintaining desired draft conditions so that the fires and the generation of combustion gases may be more uniform than is otherwise possible.

In starting the kilns or ovens the fires are limited preferably to the head ends of the grates with only sufficient air to maintain a satisfactory and substantially smokeless combustion and air is introduced if necessary above the grates to aid secondary combustion and to prevent discoloration of the brick. At the same time, suction is applied at the "dead space" and the gases withdrawn are discharged into the atmosphere, thus assisting in uniformly heating the brick and in carrying away the steam which is formed during the drying-out period. When the drying-out of the kiln has been accomplished, the fire is extended over the entire grate surface, the forced draft is increased and circulation of the combustion products is started, the circulation being regulated so as to carry the desired portion of the heat into the "dead space", thus developing uniform heat conditions throughout the length of the tunnels. From the tunnels the hot gases which are not withdrawn for recirculation pass upwardly through the kiln and the bricks therein are thus heated to a substantially uniform temperature which may be regulated to meet the required conditions by variation of the forced draft and of the recirculation. Should any portion of the kiln tend to become over-heated the recirculation is modified so that less heat is carried to that particular section. Thus, if the section of the kiln above the grates is too hot, increased recirculation will carry the heat toward the central section and if the latter section is too hot the recirculation may be decreased to permit more of the hot gases to pass into the sections above the grates.

Three easily controllable factors permit the desired distribution of the heat in the kiln: first, the amount of heat generated by the fuel can be varied by regulation of the mechanical draft; second, the application of suction at a suitable point or points permits direction of the heat to such point or points, leaving any portion to follow the natural path of the gases through the kiln; and third, the return of the hot gases to the kiln under pressure greatly assists in diverting the heat from the fuel from its natural path of least resistance to the desired points in the kiln. Furthermore, the pressure of the gases in the kiln resulting from the

forced draft and from the return of hot gases thereto forces the heat to all parts of the kiln. Thus, all sections of the kiln or oven and the objects therein are brought to the finishing point of the heat treatment uniformly in less time than by previously known methods.

It will be understood that the invention as described is applied to an updraft kiln. The same principles may be applied, however, to a down-draft kiln in which a portion of the gases is withdrawn and recirculated as described to direct the heat to the desired sections. Likewise, the invention may be applied to kilns or ovens in which articles to be heated are supported on racks.

The invention is, in fact, of general application to kilns and ovens and affords the possibility of relatively close regulation of distribution of heat in the various zones of the kiln. It also facilitates the burning of hard coal in small sizes or fine soft coal in such kilns by avoiding the effect of the necessary forced draft which has a tendency to cause the hot gases to pass through paths of least resistance to atmosphere.

The invention will be further described with reference to the accompanying drawings, in which

Fig. 1 is a vertical section through a "scove" type brick kiln;

Fig. 2 is a horizontal section on the line 2—2 of Fig. 1;

Fig. 3 is a vertical section through a "bee-hive" kiln; and

Fig. 4 is a section on the line 4—4 of Fig. 3.

Referring to the drawings, 5 indicates a honey-combed pile of brick forming the kiln which is assembled in the usual manner with tunnels 6 formed by arches 7 extending therethrough. Grates 8 are supported in the ends of the arches which are closed by metal arch-fronts 9 having firing doors 10 and ash-pit doors 11. Blast pipes 12 are connected to the ash pits and to blowers 13 which supply air under suitable pressure to maintain the blast required for the combustion of fuel on the grates. Blast gates 14 are provided to permit regulation of the quantity of air supplied.

The grates extend only part way into the tunnels. The central zones of the tunnels form a "dead space" 15 above the brick work 16. From this "dead space" pipes 17 extend to the suction side of blowers 18 which are adapted to draw hot gases from the "dead space" and to deliver them through pipes 19 to the space above the grates at the ends of the tunnels or through pipes 19' controlled by blast gates 20' to the air. Blast gates 20 are provided in the pipes 19 to regulate the flow of hot gases. Pipes 21 with blast gates 22 therein are connected to the suction sides of the blowers 18 and to

the atmosphere, to permit the introduction of regulated quantities of air with the hot gases. Gas mixers 20" (similar to those used on domestic gas stoves) may be placed in the pipes 19 to draw air by inspiration into the pipes. The amount of air thus introduced can be regulated by the usual shutters provided in such mixers. Pipes 24 may connect the pipes 19 to the space beneath the grates to permit a portion of the hot gases to be introduced under the grates, blast gates 25 being provided in the pipes to permit regulated operation.

In the operation of the kiln as described the fires are started on the head ends of the grates and held there for a sufficient period to permit drying out of the kiln by regulation of the amount of air supplied by the blowers. During this period a portion of the hot gases from the "dead space" may be withdrawn and discharged to the atmosphere. When the drying-out period is completed the blast beneath the grates is increased and the fires are spread over the grates so that the temperature of the gases rises rapidly. Thereupon the hot gases are circulated through the system with the addition of air if desired. The amount of circulation is regulated to create the currents necessary to carry the heat in the hot combustion gases in a regulated and uniform manner throughout the extent of the tunnels and particularly into the "dead space" so that that portion of the gases which rises through the honey-combed pile of bricks carries the heat uniformly to all of the bricks in the kiln, the bricks being thereby raised uniformly to the desired high temperature for the purpose of completing the burning operation. The amount of air introduced with the hot gases can be regulated as may be necessary to obtain the desired oxidizing or reducing atmosphere which likewise will be uniform throughout the kiln. Consequently the burning of the bricks will be conducted so as to be completed uniformly; no portions of the arches or of the bricks overlying the arches in the kiln will be overheated, and a uniform product can be obtained in the shortest possible period. The period of burning is shortened materially by the fact that radiation and conduction are not relied upon to carry the heat to any portion or zone of the kiln. All of the zones are subjected to the heating effect of the hot combustion gases, the pressure these gases are under aiding in permeating all parts of the kiln. Should any zone of the kiln tend to overheat the circulation of the hot gases can be increased or reduced to carry the surplus heat away from that particular zone and toward another zone where the temperature is lower. The circulation can be modified from time to time as may be required to accomplish the desired object.

The foregoing description relates particularly to a kiln of the "scove" type. The principles described are applicable, however, to "bee-hive" kilns and to other kilns and ovens. 5 In Figs. 3 and 4 of the drawing a "bee-hive" kiln is illustrated which is provided with permanent walls 26 within which the bricks 27 are arranged in a honey-combed pile leaving a flue 28 between the permanent wall of 10 the kiln and the pile of bricks. Furnaces 29 are arranged at intervals about the kiln and are connected to the flue 28 by passages 30. Grates 31 are arranged in the furnaces and are supplied with fuel through firing doors 15 32. The air to maintain combustion is supplied through pipes 33 from blowers 34, the pipes 33 being connected to the ash pits 35 and blast gates 36 being arranged to permit the regulation of the quantity of air delivered to the respective furnaces. 20

The hot combustion gases pass through the flue 28 and downwardly through the pile of brick, a portion of the gases escaping through a flue 37 which may be connected to 25 the smoke stack (not shown).

To permit operation of the method as described flues 38 are arranged in the base of the kiln, being connected to the zones of the kiln which are not in the direct path of the 30 hot gases to the flue 37. The hot gases may be withdrawn through the flues 38 by blowers 39 which return the hot gases through pipes 40 to the furnaces 29 above the grates. Air inlets 41 with blast gates 42 are provided 35 to permit the introduction of the desired quantity of air with the hot gases or mixers 41' can be used as before mentioned. Blast gates 43 permit the regulation of the quantity of hot gases which are circulated.

40 The operation of the apparatus as described is substantially as in the preceding embodiment of the invention, that is to say, the fires are started in the grates with a limited supply of air to avoid excessive heating 45 and the hot gases are permitted to circulate through the kiln during the drying-out operation, a portion of the gases being withdrawn through the flues 38 and discharged to the atmosphere through pipes 44 and blast 50 gates 45. When drying out is completed the blast is increased to rapidly raise the temperature of the hot gases and portions of the gases are recirculated and returned to the furnaces to mingle with the fresh combustion 55 gases from the fires. This ensures the regulated distribution of the hot gases throughout the kiln and the consequent uniform burning of the brick. Air is introduced or shut off as required to maintain the desired oxidizing or reducing conditions. 60

As will be understood from the foregoing description, the invention depends upon the creation of currents of hot gases flowing from the source thereof toward zones beyond 65 the normal direct path of the gases through

the kiln or to points requiring greater heat. The currents are provided by withdrawing a portion of the gases from the "dead space" and these gases are returned to the space where the hot gases are generated so that substantially none of the heat is lost.

While the invention has been described especially with reference to brick kilns, it will be understood that the principles thereof are applicable to kilns and ovens designed 75 for various purposes and that changes may be made in the operation and in the details of the apparatus employed without departing from the invention or sacrificing any of the advantages thereof. 80

I claim:

1. The method of operating kilns and the like, which comprises distributing hot combustion gases in the kiln by withdrawing a portion of such gases from a zone therein 85 beyond the normal direct line of travel of the gases through the kiln and returning the gases withdrawn to the kiln at another zone.

2. The method of operating kilns and the like, which comprises distributing hot combustion gases in the kiln by withdrawing a portion of such gases from a zone therein 90 beyond the normal direct line of travel of the gases through the kiln, returning the gases withdrawn to the kiln at another zone and regulating the distribution of the gases by varying the quantity thereof which is withdrawn and returned. 95

3. The method of operating kilns and the like, which comprises distributing hot combustion gases in the kilns by withdrawing a portion of such gases from a zone therein 100 beyond the normal direct line of travel of the gases through the kiln, returning the gases withdrawn to the kiln at another zone 105 and introducing combustion-supporting gas to the latter zone. 110

4. The method of operating kilns and the like, which comprises generating combustion 115 gases in a combustion zone, distributing the hot combustion gases in the kiln by withdrawing a portion of such gases from a zone beyond the combustion zone and out of the normal direct line of travel of the gases through the kiln and returning the gases withdrawn to the combustion zone. 120

5. The method of operating kilns and the like, which comprises generating combustion gases in a combustion zone, distributing the hot combustion gases in the kiln by withdrawing a portion of such gases from a zone beyond the combustion zone and out of the normal direct line of travel of the gases through the kiln, returning the gases withdrawn to the combustion zone and regulating the distribution of the gases by varying the quantity thereof which is withdrawn and returned. 125

6. The method of operating kilns and the like, which comprises generating combustion 130

gases in a combustion zone, distributing the hot combustion gases in the kiln by withdrawing a portion of such gases from a zone beyond the combustion zone and out of the normal direct line of travel of the gases through the kiln, returning the gases withdrawn to the combustion zone and introducing combustion-supporting gas to the latter zone.

10 7. The method of operating kilns and the like, which comprises maintaining the combustion of fuel with a forced draft of combustion-supporting gas, thereby generating hot combustion gases in a combustion zone, 15 distributing the hot combustion gases in the kiln by withdrawing a portion thereof from a zone beyond the combustion zone and out of the normal direct line of travel of the gases through the kiln and returning the 20 gases withdrawn to the combustion zone.

8. The method of operating kilns and the like, which comprises maintaining the combustion of fuel with a forced draft of combustion-supporting gas, thereby generating hot combustion gases in a combustion zone, 25 distributing the hot combustion gases in the kiln by withdrawing a portion thereof from a zone beyond the combustion zone and out of the normal direct line of travel of the gases 30 through the kiln, returning the gases withdrawn to the combustion zone and regulating the distribution of the gases by varying the quantity thereof which is withdrawn and returned.

35 9. The method of operating kilns and the like, which comprises maintaining the combustion of fuel with a forced draft of combustion-supporting gas, thereby generating hot combustion gases in a combustion zone, 40 distributing the hot combustion gases in the kiln by withdrawing a portion thereof from a zone beyond the combustion zone and out of the normal direct line of travel of the gases through the kiln, returning the gases 45 withdrawn to the combustion zone and introducing combustion-supporting gas to the latter zone.

10. The method of operating brick kilns, which comprises arranging the bricks in a 50 honey-combed pile with tunnels extending through the base thereof, burning fuel at the opposite ends of the tunnels to produce combustion gases therein, distributing the hot combustion gases in the tunnels by withdrawing a portion thereof from the central 55 zones of the tunnels and returning the gases withdrawn to the ends of the tunnels.

11. The method of operating brick kilns, which comprises arranging the bricks in a 60 honey-combed pile with tunnels extending through the base thereof, burning fuel at the opposite ends of the tunnels to produce combustion gases therein, distributing the hot combustion gases in the tunnels by with-

drawing a portion thereof from the central zones of the tunnels, returning the gases withdrawn to the ends of the tunnels and regulating the distribution of the gases by varying the quantity thereof which is withdrawn and returned.

12. The method of operating brick kilns, which comprises arranging the bricks in a honey-combed pile with tunnels extending through the base thereof, burning fuel at the opposite ends of the tunnels to produce 75 combustion gases therein, distributing the hot combustion gases in the tunnels by withdrawing a portion thereof from the central zones of the tunnels, returning the gases withdrawn to the ends of the tunnels and introducing combustion-supporting gas at the ends of the tunnels.

13. The improvement in kilns and the like, which comprises means for supplying hot combustion gases thereto and means for 85 distributing the hot gases in the kiln, including means for withdrawing a portion of the gases from a zone remote from the source of such gases and out of the normal direct path of the gases through the kiln 90 and means for returning the gases to the kiln at the source of the gases.

14. The improvement in kilns and the like, which comprises means for supplying hot combustion gases thereto and means for 100 distributing the hot gases in the kiln, including means for withdrawing a portion of the gases from a zone remote from the source of such gases and out of the normal direct path of the gases through the kiln, means for returning the gases to the kiln at the source of the gases and means for introducing combustion-supporting gases with the gases returned.

15. The improvement in brick kilns and the like, comprising a honey-combed pile of bricks with tunnels at the base thereof, grates for solid fuel at the ends of the tunnels and means for distributing the hot gases in the kiln, including means for withdrawing a portion of the gases from dead spaces between the grates and means for returning the gases to the tunnels above the grates.

16. The improvement in brick kilns and the like, comprising a honey-combed pile of bricks with tunnels at the base thereof, grates for solid fuel at the ends of the tunnels, and means for distributing the hot gases in the kiln, including means for withdrawing a portion of the gases from dead spaces between the grates, means for returning the gases to the tunnels above the grates and means for introducing combustion-supporting gases above the grates.

In testimony whereof I affix my signature.

CHARLES H. CAMP.
